UNITED STATES PATENT OFFICE.

DANIEL WESLEY KEITH, OF KEITHVILLE, LOUISIANA.

LAUNDRY-MACHINE.

SPECIFICATION forming part of Letters Patent No. 693,030, dated February 11, 1902.

Application filed October 6, 1900. Renewed December 26, 1901. Serial No. 87,310. (No model.)

To all whom it may concern:

Be it known that I, DANIEL WESLEY KEITH, a citizen of the United States, residing at Keithville, in the parish of Caddo and State 5 of Louisiana, have invented a new and useful Laundry-Machine, of which the following is a specification.

My invention is an improved laundry-machine which is adapted for starching collars 10 and cuffs, pressing the superfluous starch therefrom, drying the same after they are starched, and subsequently dampening the same, thereby placing the cuffs and collars in condition to be ironed.

15 My invention consists in the peculiar construction and combination of devices herein-after fully set forth, and pointed out in the claims.

In the accompanying drawings, Figure 1 is 20 a vertical longitudinal sectional view of a laundry-machine embodying my improvements. Fig. 2 is a sectional view of the same, taken on the line *a a* of Fig. 1. Fig. 3 is a similar view taken on the line *c c* of Fig. 1. 25 Fig. 4 is a similar view of the same, taken on the line *d d* of Fig. 1. Fig. 5 is a detail view showing the means for adjusting the pressing, drying, and moistening rolls. Fig. 6 is a detail view of one of the scrapers. Fig. 7 is a 30 detail view of one of the discharge-rollers.

In the embodiment of my invention I provide a suitable frame 1, in one end of which is a starch tank or receptacle 2. In the sides of the starch-tank are the bearings of a series 35 of rollers 3, which I will call the "starching-rollers" and certain of which are submerged in the starch-tank, as indicated in Fig. 1. At the front end of the frame are a pair of feed-rollers 4, one of which is disposed above the 40 other. In rear of the starching-rollers are the series of pressing-rollers 5, of which there are any suitable number, two pairs of said pressing-rollers being here shown. The said pressing-rollers, which are made of metal, are per- 45 forated and are covered with any suitable ab- sorbent material, as at 6. Beyond the press- 50 ing-rollers are a series of drying-rollers 7, of which there are a suitable number. As here shown, there are three pairs of the drying- rollers, and said drying-rollers are of greater diameter than the pressing-rollers. Beyond the drying-rollers are the moistening-rollers 8, of which there are a suitable number. As here shown, there are two pairs of moistening-

rollers. Beyond the moistening-rollers are 55 the discharge-rollers 9, there being a pair thereof, one being disposed above the other and spaced a suitable distance apart.

The moistening-rollers are hollow and per- 60 forated, being made of suitable metal, and are covered between the grooves with suit- 65 able absorbent material, as at 10. The jour- nals of the said moistening-rollers are hollow, and suitable steam-pipes discharge into said moistening-rollers to supply the said moisten- 70 ing-rollers with steam, which by condensing keeps the covers 10 of said rollers moist, as will be understood. The drying-rollers 7 are also hollow and have hollow journals and steam-pipes which discharge through said hol- 75 low journals, whereby steam at a suitable pressure is maintained in said drying-rollers to keep the latter heated to the requisite de- gree.

A guide-roller 11 is journaled in suitable 80 supports above the central portion of the starch-tank. A guide-roller 12 is journaled in suitable supports below the central portion of the starch-tank, and a suitable direc- 85 tion-roller 13 is journaled at a suitable dis- tance below the front end of the starch-tank. The guide-rollers 11 12 have vertically-mov- able bearings, as at 14, and are provided with adjusting-screws 15, by which they may be adjusted. Adjusting-screws 15 are also pro- 90 vided for adjusting the pressing, drying, and moistening rollers.

A series of endless traveling carrier-wires 16 connect the upper feed-roller 4 and the upper discharge-roller 9, pass over the guide- 95 roller 11, alternately under and over the starch- 100 ing-rollers 3, throughout the series thereof, and under the upper series of pressing-rollers 5, drying-rollers 7, and moistening-rollers 8. A series of endless traveling carrier-wires 17 105 connect the lower feed-roller 4 and the lower discharge-roller 9, pass alternately under and over the starching-rollers in the same planes as the opposing leads of the carrier-wires 16, pass over the lower series of pressing-rollers 5, drying-rollers 7, and moistening-rollers 8, and pass under the guide-roller 12 and direc- 110 tion-roller 13. The said carrier-wires 16 115 120 125 130 135 140 145 150 155 160 165 170 175 180 185 190 195 200 205 210 215 220 225 230 235 240 245 250 255 260 265 270 275 280 285 290 295 300 305 310 315 320 325 9865 9870 9875 9880 9885 9890 9895 9900 9905 9910 9915 9920 9925 9930 9935 99

respectively provided. The pressing-rolls are also provided with triangular grooves corresponding in size and number with those in the moistening-rolls. A suitable number 5 of the endless traveling carrier-wires 16 17 are employed, and the same are disposed at appropriate regular distances apart on the rollers. Series of endless traveling fender-wires 18 19 connect the respective upper and 10 lower drying and discharge rollers 7 9 and operate in annular grooves 7^b, 8^b, and 9^b, with which said drying, moistening, and discharge rollers are respectively provided. It will be 15 observed by reference to the drawings that the opposing leads of the fender-wires 18 19 between the drying-rollers are disposed in planes which are slightly spaced apart vertically, and it will be further observed that the 20 said fender-wires are disposed intermediate of the carrier-wires 16 17. Said carrier-wires and said fender-wires project beyond the surfaces of the drying-rollers 7, as shown, and the collars and cuffs which are carried between the said drying-rollers by said carrier 25 and fender-wires are by the said wires kept out of direct contact with the said rollers, while subjected by close proximity thereto to the heat radiated therefrom and effectually dried by said rollers.

30 The operation of my invention is as follows: The collars and cuffs are fed by an attendant between the feed-rollers 4 to the series of carrier-wires 16 17 and are by the said carrier-wires and by the starching-rollers 3 carried 35 through and submerged in the starch in the starch-tank. After leaving the starch-tank the collars and cuffs are subjected to the compression of the compressing-rollers 5, which remove or express superfluous starch therefrom. 40 Immediately after passing the pressing-rollers the collars and cuffs are by the co-acting carrier and fender wires passed between and proximate to the drying-rollers and dried, as hereinbefore stated, and after 45 leaving the drying-rollers the collars and cuffs pass between the moistened surfaces of the moistening-rollers, which serve to dampen them before being discharged from the machine, and hence the collars and cuffs when 50 they are discharged from the machine are in condition to be ironed.

At a suitable point, preferably above the guide-roller 11, I provide a scraper 20, which scrapes the starch from the carrier-wires 16. 55 A similar scraper 21 scrapes the starch from the carrier-wires 17.

Any suitable means may be employed for operating the rollers. It will be understood that as the carrier-wires connect and engage 60 all the rollers the latter are rotated when power is applied to any one of them, which may be done by a power-pulley or sprocket-wheel to engage a power belt or chain driven by any suitable engine. A sprocket-wheel is 65 shown attached to the shaft of one of the rollers 7 for this purpose.

Having thus described my invention, I claim—

1. In a laundry-machine of the class described, the combination of a starch-tank, 70 starching-rollers therein, endless traveling carrier elements coacting with said starching-rollers, pressing-rollers beyond said starching-rollers and to which said endless traveling carrier elements lead, drying-rollers beyond 75 said pressing-rollers, moistening-rollers beyond the said drying-rollers, said drying and moistening rollers being engaged by said carrier elements, and endless traveling fender elements engaging the opposing sides of 80 said drying-rollers and disposed parallel to said endless traveling carrier elements, substantially as described.

2. In a laundry-machine of the class described, the combination of a starch-tank, 85 starching-rollers therein, endless traveling carrier elements coacting with said starching-rollers, pressing-rollers beyond said starching-rollers and to which said endless traveling carrier elements lead, drying-rollers beyond 90 said pressing-rollers, moistening-rollers beyond said drying-rollers, said drying and moistening rollers being engaged by said endless traveling carrier elements, and scrapers for said endless traveling carrier elements, 95 substantially as described.

3. In a laundry-machine of the class described the combination of a starch-tank, starching-rollers therein, endless traveling carrier-wires coacting with said starching-rollers, pressing-rollers beyond said starching-rollers, and to which said endless traveling carrier-wires lead, drying-rollers beyond 100 said pressing-rollers and moistening-rollers beyond said drying-rollers, substantially as 105 described.

4. In a laundry-machine of the class described, the combination of a starch-tank, starching-rollers therein, endless traveling carrier-wires coacting with said starching-rollers, pressing-rollers beyond said starching-rollers, drying-rollers beyond said pressing-rollers and moistening-rollers beyond 110 said drying-rollers, said endless traveling carrier-wires engaging the said pressing, drying and moistening rollers and fender-wires traveling on said drying-rollers, the opposing 115 leads of said fender-wires being disposed parallel to said carrier-wires, said carrier-wires and fender-wires projecting beyond the opposing surfaces of said drying-rollers to prevent the work from coming in direct contact with said drying-rollers, substantially as described.

In testimony that I claim the foregoing as 125 my own I have hereto affixed my signature in the presence of two witnesses.

DANIEL WESLEY KEITH.
